UNITED STATES PATENT OFFICE.

EDWARD E. WAKEFIELD, OF PROVIDENCE, RHODE ISLAND, ASSIGNOR TO HALKYARD MANUFACTURING COMPANY, OF PROVIDENCE, RHODE ISLAND, A CORPORATION OF RHODE ISLAND.

LACING-STUD-SETTING MACHINE.

1,234,982.

Specification of Letters Patent. Patented July 31, 1917.

Application filed February 13, 1915. Serial No. 8,113.

To all whom it may concern:

Be it known that I, EDWARD E. WAKEFIELD, a citizen of the United States, and resident of the city of Providence, in the 5 county of Providence and State of Rhode Island, have invented certain new and useful Improvements in Lacing-Stud-Setting Machines, of which the following is a specification.

10 This invention relates to improvements in machines for automatically setting lacing studs such as hooks or eyelets in shoe uppers, and has for its object to provide means adapted to work in conjunction with such a 15 machine for feeding a strip of reinforcing tape to the shoe upper to be connected to the upper by the setting of the lacing studs thereinto, this tape to serve as a support, reinforcement or backing for the thin upper 20 per and to prevent the studs from pulling out. This invention is an improvement on my co-pending patent application Serial No. 845,939.

A further object of this invention is to 25 provide means whereby the strip may be readily severed after the required length has been connected to the upper.

A further object of this invention is the 30 provision of means whereby the strip may be partially severed if desired as it is being laid on and connected to the upper, to cause the strip to conform more readily to the curve of the upper without wrinkling or buckling.

35 It is found in practice in the attaching of lacing studs such as hooks or eyelets to the shoe upper that in the better qualities of goods, it is desirable to sever the backing strip into a length for each individual stud 40 which will cause this backing to lie flat upon the surface of the upper while being laid in a curve to follow the natural form of the edge of the upper without wrinkling or buckling, the mechanism for accomplishing 45 which, is set forth in my prior patent application above referred to, but in the lower grade of goods where the stock is thin and lacking in strength, I preferably apply this backing strip to the upper in a single length 50 without severing the same between the studs. In this way the maximum reinforcing effect is obtained from the backing strip to strengthen the stock not only about the studs but between the same when set.

55 Then again in applying this backing strip

to the medium grade of uppers, it is sometimes found advisable to cut or notch the edge of the strip to allow or permit it to better conform to the curve of the upper as it is attached thereto, to avoid in a measure 60 its wrinkling or buckling when laid in a curved form.

With these and other objects in view, the invention consists of certain novel features of construction, as will be more fully described, and particularly pointed out in the appended claims.

In the accompanying drawings:

Figure 1— is a front elevation of the feeding head partly in section showing the 70 presser foot in engagement with the work and the reinforcing tape as being connected to the work by a plurality of lacing studs, and a severing blade being raised so as not to cut the strip when the punch descends. 75

Fig. 2— is a view of the mechanism illustrated in Fig. 1 showing the punch raised after having set the last stud in the upper and the presser foot in extreme raised position causing the knife to sever the strip. 80

Fig. 3— is a side elevation showing a portion of the feeding head and the mechanism through which the presser foot is raised to cause the tape to be brought into contact with the edge of the knife and severed. 85

Fig. 4— is a plan view of the presser foot showing the guide block through which the tape is fed, as slidably mounted in said foot.

Fig. 5— is a face view of the knife blade showing the edge set on an angle to the 90 plane of the strip whereby it may be adjusted to partially sever the strip between the studs when desired.

Fig. 6— is a view of the inner side of the shoe upper showing the reinforcing tape in 95 one continuous piece all connected to the upper by the setting of the studs.

Fig. 7— shows the reinforcing tape as connected to the shoe upper and this tape as having been partially severed between the 100 studs.

In the accompanying drawings I have illustrated a hook setting machine with my tape feeding and severing mechanism operatively connected thereto, but the same is as 105 well adapted for use on an eyelet setting machine, as the strip serves as a reinforcement for either a hook or eyelet, and I have, therefore, adopted the term "lacing stud", which is used throughout the specification 110

and claims and is intended to include both the hook and the eyelet.

In the accompanying drawings and specification, I have shown and described only 5 sufficient mechanism to illustrate my present invention.

In the drawings 10 designates a portion of the carriage in which is mounted the punch spindle 11 and the presser foot spindle 12, the latter spindle being supported from the former by the collar or guide blocks 13 and 14. To this spindle 11 is connected the punch 15 which forms holes in the upper *b* and also in the strip of stiffened reinforcing tape 16 for the reception of the lacing studs 17, the cutter blade 18 is also shown as being mounted in the blocks 13 and 14 to move with the punch spindle. This cutter is provided on one of its faces 20 with rack teeth 19 which are engaged by the pinion 20, the latter being provided with an operating handle 21, the rotation of which causes the plate 18 to be raised and lowered relative to the spindle carrying the same. 25 A clamping member 22 is provided to engage the head 21 of the pinion 20 to bind and retain the same in any desired position after the knife has been set. By this arrangement, it will be seen that the knife 30 blade may be adjusted vertically, whereby it may be set so as to sever the tape at each setting operation of the stud or it may be raised so as not to sever the tape except when the presser foot raises the tape up into contact 35 with said blade or again the knife blade may have its edge formed on an angle to the plane of the strip and by this adjusting mechanism the knife may be set to sever just the desired portion of one edge of the strip 40 as the punch descends to set the stud. By this means the same machine may be adjusted to perform several classes of work. The guide block 23 is connected to the presser foot spindle 22 and is provided with a longitudinal aperture 24 through it which 45 serves as a guide through which the strip 16 passes, and by which the strip is accurately guided over or to the upper which it is to be laid on and connected in the desired 50 position thereto.

The outer edge of this block is provided with a hardened plate 25 having an aperture through which the tape also passes and this plate serves to coöperate with the edge 55 26 of the cutter 18, whereby the latter is caused to slide upon that of the former and when it is desired to have the two coöperate the guide block 23 with its plate 25 is raised sufficiently toward the edge of the blade to 60 sever the strip passing therethrough.

This block 23 is mounted to slide longitudinally in the presser foot proper 27, see Fig. 4, which presser foot is connected through the arm 28, member 29 and spring pressed 65 spindle 30 to be operated from the foot

treadle 31 through the connection 32 and lever 33 pivoted at 34, whereby when it is desired to raise the presser foot to set the work, this treadle is pressed down slightly to permit the work to be entered, adjusted 70 or removed therefrom; but when it is desired to sever the strip the presser foot is raised still further causing the two cutter members 25 and 26 to coöperate and sever the strip which raising action is obtained by a little 75 further pressure of the foot upon the treadle. By this construction, it will be seen that the strip may be severed at any place desired by a simple operation of the foot treadle which raises the combination cutter and 80 guide block up sufficient to coöperate with the cutter plate.

In the operation of my improved device the tape 16 is led from a reel, not shown, through a suitable guide 35 supported from 85 the arm 36 which is connected to the presser foot 27, see Fig. 4. In this guide, I have mounted a tension spring 37 which permits the tape to advance but prevents the same from receding or moving backward during 90 the return stroke of the feeding mechanism. From this guide the tape is led through the aperture 24 in the guide block 23 above the engaging surface of the presser foot and over the cutting edge of the cutter plate 25. 95

In setting the machine for the operation of applying a backing strip to the upper *b*, the end of the strip is advanced by hand beyond the cutting edge of the block 23 beneath the punch 15. The punch now descends into the position illustrated in Fig. 1 100 piercing the strip and the upper and then with a lateral motion moves both the strip and upper into the next position over the pocket plate 38 which latter coöperates with the punch to set and rivet the studs in the upper and at the same time secures the reinforcing strip to the back thereof. The punch spindle is now raised and moved to the right a distance equal to that between the 105 studs, while the upper is held in fixed position by the presser foot. The operation above described is repeated at the setting of each stud, the movement of the head to the left serving to draw out the strip and the 110 setting of the studs secures the strip and the upper together. When the desired number of studs have been set into the upper and strip the head is stopped in the advanced 115 position illustrated in Fig. 2 and the operator presses his foot upon the treadle 31 and raises the presser foot and guide block 27 until the knife edge 26 engages and severs the strip. The upper is now removed from the machine and another positioned herein 120 and the presser foot lowered to retain the same.

The next movement of this head in beginning its operation upon the fresh upper is to the right, which causes the strip to 125 130

extend the desired distance beyond the punch, the next operation forces the punch down through the projecting end of the strip and the operation of setting the studs 5 in this upper is repeated in the manner above described.

By the laying of a full or unsevered strip onto the back of the upper, it will be seen that the maximum support is obtained, that 10 is, the strip not only serves as a support about the stud but also serves as a support between the different studs to stiffen and strengthen the upper materially along its edge at the point where greatest strain is 15 exerted.

In some instances, I have provided a 20 knife blade 39 having a cutting edge 40 set at an angle to the face of the strip as illustrated in Fig. 5 and when this blade is lowered by means of the rack and pinion 19 and 20 its point 41 will pass through the edge of the strip 16 and partly sever the same by which arrangement I secure the effect illustrated in Fig. 7, which as will be 25 seen permits the strip to more readily conform to the curved edge of the upper without wrinkling or buckling.

I have shown and described one form of mechanism for attaching the strip to the 30 upper by setting a plurality of studs therein but any means for performing this function will fall within the spirit and scope of this invention.

I claim:

35 1. In a lacing stud setting machine the combination with a guide for a continuous reinforcing strip to prevent its lateral displacement in both directions and direct the same to the work, of step by step means for advancing the strip through said guide, and means for attaching said strip to the work by the setting of a plurality of studs at intervals through a length of said strip when advanced to the work.

45 2. In a lacing stud setting machine the combination with a guide for a continuous reinforcing strip to prevent its lateral displacement in both directions and direct the same to the work, of means for attaching said strip to the work by the setting of a plurality of studs at intervals through a length of said strip when advanced to the work, both said work and strip being fed simultaneously after each setting operation.

55 3. In a lacing stud setting machine, means for feeding the work and a reinforcing strip an equal distance and simultaneously, means for setting a plurality of studs through both the strip and the work for attaching said strip to the work, and means for severing the applied length of strip from the rest of the strip.

65 4. In a lacing stud setting machine, means including a punch for setting studs, means for causing said setting means to feed a

continuous reinforcing strip with a shoe upper and set a plurality of studs through both and means for partly severing the strip at intervals when desired.

5. In a lacing stud setting machine, means 70 for setting studs, means for causing said setting means to feed a continuous reinforcing strip with a shoe upper, and set a plurality of studs through both, and means whereby the strip may be partially severed 75 when desired.

6. In a lacing stud setting machine, means 80 for setting studs, means for causing said setting means to feed a continuous reinforcing strip with a shoe upper and set a plurality of studs through both connecting them together, and manually operated means for severing the strip when desired.

7. In a lacing stud setting machine, means 85 for feeding the work and a reinforcing strip an equal distance and simultaneously, means for setting studs through both the strip and the work for attaching the two together, and means whereby the strip may be partially severed transversely at intervals. 90

8. In a lacing stud setting machine, a 95 guide for leading a continuous reinforcing strip of material over a shoe upper, a punch for forming a stud receiving hole in both the reinforcing strip and the upper, means whereby said punch is caused to impart a step by step feeding movement to both the strip and upper and means for setting studs in the holes punched.

9. In a lacing stud setting machine, a 100 punch for forming a stud receiving hole in both a reinforcing strip and a shoe upper, means whereby said punch is carried to impart a step by step feeding movement to both the strip and upper, and means for 105 severing the strip.

10. In a lacing stud setting machine, a 110 guide for a continuous reinforcing strip to prevent its lateral displacement in both directions and direct the same to the work, a punch for forming a stud receiving hole in both a reinforcing strip and a shoe upper, and means whereby said punch is caused to impart a step by step feeding movement to both the strip and upper, said strip being 115 secured to the upper by the setting of a plurality of studs through both.

11. In a lacing stud setting machine, means including a punch for setting studs, and means for guiding a strip of reinforcing tape to a shoe upper, said setting means being adapted to feed said strip with the upper and the latter being secured to the upper by the setting of studs through both. 120

12. In a lacing stud setting machine, 125 means for setting studs, means for guiding a strip of reinforcing tape to a shoe upper, said setting means being adapted to feed said strip with the upper and the latter being secured to the upper by the setting of 130

studs through both, and means in said guide for assisting in severing the strip when desired.

13. In a lacing stud setting machine, 5 means including a punch for setting studs, means for guiding a strip of reinforcing tape to a shoe upper, said setting means being adapted to feed said strip with the upper and the latter being secured to the upper 10 by the setting of studs through both, and means for partially severing the strip intermediate the studs.

14. In a lacing stud setting machine, a punch for forming a stud receiving hole in 15 both a reinforcing strip and a shoe upper, means whereby said punch is caused to impart a feeding movement to both the strip and upper, said strip being secured to the upper by the setting of a plurality of 20 studs through both, and adjustable severing

means for completely or partially severing the strip as desired.

15. In a lacing stud setting machine, means including a punch for setting studs, means for guiding a strip of reinforcing 25 tape to a shoe upper, said setting means being adapted to feed said strip with the upper and the latter being secured to the upper by the setting of studs through both, means in said guide for assisting in severing the 30 strip when desired, and means for holding said strip after having a length severed therefrom while the feeding means return to engage the same.

In testimony whereof I affix my signature 35 in presence of two witnesses.

EDWARD E. WAKEFIELD.
